UNITED STATES PATENT OFFICE.

HENRY M. RYDER, OF TAUNTON, MASSACHUSETTS, ASSIGNOR OF ONE-HALF TO JOHN F. MONTGOMERY, OF SAME PLACE.

URN FOR STOVES.

SPECIFICATION forming part of Letters Patent No. 252,330, dated January 17, 1882.

Application filed November 14, 1881. (No model.)

To all whom it may concern:

Be it known that I, HENRY M. RYDER, of Taunton, in the county of Bristol and State of Massachusetts, have invented certain new and useful Improvements in Urns for Stoves, of which the following is a specification.

My invention relates to urns which are attached to stoves having a hinged cover; and it consists in a novel arrangement for keeping the urn positively in a vertical position, the object being to keep the water therein from running out when the cover of the stove is raised and prevent the oscillations of the urn caused by a quick movement of the cover.

The accompanying drawings illustrate the manner of accomplishing the object of my invention.

Figure 1 is a side elevation of the top part of a stove with my improved device for keeping the urn in a vertical position. Fig. 2 is the same, with the cover turned up. Fig. 3 is a transverse vertical section through Fig. 1.

The cover A is hinged at *a* to the top of the

stove in the usual way. The urn B is journaled to the cover A by a pin, *b*, passing through it and the upper part of the cover A.

A link, *D*, is hinged at one end to a stud, *d*, fast to the urn, and at the other end to a stud, *d'*, which is fast to the stove. The link *D* serves as a radius-bar, keeps the urn from tipping when the cover is raised, and maintains it positively in its proper position, thereby preventing the oscillations to which urns as heretofore mounted on hinged covers are liable, and which are likely to occur to an extent sufficient to throw out some of the water when the cover is quickly raised or lowered.

I claim as my invention—

The combination, with the urn, the hinged cover, and the stove, of a link hinged to the urn and the stove, substantially as described.

HENRY M. RYDER.
